UNITED STATES PATENT OFFICE.

RUSSELL E. IRISH, OF DORMONT, PENNSYLVANIA.

WIRE-TESTING DEVICE.

Application filed March 26, 1926. Serial No. 97,525.

This invention relates to a device for estimating the pressure exerted by wire, and particularly to a device for estimating the pressure exerted by flexed wire when used 5 in orthodontia or the straightening of teeth.

In the straightening of teeth it is of great importance that the straightening wire be of such grade and so arranged that it will exert a pressure sufficient to gradually move 10 the tooth in its socket, and that the pressure exerted should not be so great as to loosen the tooth or work injury to its nerve connections. For this reason it is highly desirable that means for exactly estimating 15 the pressure exerted by the straightening wire in the position of its use should be utilized prior to the attachment of the wire to the teeth.

The object of the present invention is to 20 provide a device which is positive in its operation, and which will estimate exactly the pressure exerted by a straightening wire in the exact position of its application to the teeth, and the pressure exerted by the 25 straightening arch which carries the straightening wire proper.

Further objects of the invention are to 30 provide a device for this purpose which is relatively simple, and in which the various elements are so constructed and arranged as 35 to permit the testing operation to be quickly and easily performed.

In the accompanying drawings Figure 1 is a plan view of the device of the present 35 invention, showing a wire mounted in the wire holding means of the device prior to a test for estimating the pressure to be exerted by such wire; Figure 2 is a plan view of the device, illustrating the actual testing 40 operation; Figure 3 is a vertical sectional view through the device illustrating the operation shown in Figure 2; Figure 4 is a vertical sectional view through one of the binding posts for holding the wire; Figure 45 5 is a plan view of the indicating mechanism of the device, with the calibrated cover of the indicating mechanism removed; Figure 6 is a detail view partly in longitudinal section of the wire contacting member associated with the indicating means; Figure 50 7 is a side elevation of the device, showing the use of an attachment for making a different estimation of pressure exerted by a wire; Figure 8 is a front elevation showing 55 such attachment in detail on the section line 7-7 Figure 8; Figure 9 is a vertical

sectional detail view through one of the binding posts of the attachment taken on the line 9-9 of Figure 8; Figure 10 is a fragmentary plan view illustrating a use of 60 the device; and Figure 11 is another fragmentary plan view illustrating another use of the device.

As illustrated, the device comprises a box or case 1, having a top or cover 2. On the 65 top or cover 2 are a pair of tracks or ways 3 in which a platform 4 is slidable. On one of the tracks 3 is a scale 5, while the platform is provided with an indicating mark or line 6 for showing distance moved by the 70 platform with reference to the scale. Secured to the under side of platform 4 is a lug or nut 7 which extends downwardly through a slot 8 in the cover 2. An actuating shaft 9 has a screw threaded portion 75 10 engaging the nut lug 7. This shaft 7 has its bearings in lugs 11 and 12, which are shown integral with the cover 2, and is rotated by means of a wheel 13 extending above the cover. This wheel is marked in 80 subdivisions, so that it gives a micrometer reading of movement of the platform. As the scale 5 on one of the tracks 3 is in millimeters, the micrometer scale 14 on the wheel 13 is desirably in hundredths of millimeters. 85

The wire holding means of the device comprise a rotatable member or turn table 15, which is rotatably mounted on the platform 4 by the same screw 16 which secures the nut 7 to the platform. A threaded handle member 17 provides a convenient means for rotating the turn table, and for holding it in adjusted position. Secured to the platform 4, and embracing the turn table 15 is a segmental scale 18 for measuring angular adjustment of the turn table on the platform 4. On the rotatable member or turn table 15 is a track 19 which is substantially enclosed to provide an internal path 20 and slot 21. Slidably mounted in the 100 track 19 are two similar binding posts 22. Each of the binding posts comprises a tubular stem 23 which rests on the track, and a rod 24, which has a foot 25 engaging in the path 20 of the track and a screw threaded portion 26 extending above the upper end of the stem. A cap member 27 engages on the portion 26 of the rod, so that it may be moved upwardly or downwardly with respect thereto to release or clamp a wire A 110 in the binding post. A freely rotatable washer 27^a surrounds the rod 24, and is dis-

posed between the stem 23 and cap 27, so that rotation of the cap does not tend to twist the arch wire A. A coiled spring 28 is inserted in a seat in the upper portion 5 of stem 23 in position to surround the rod 24 and bear directly against the washer 27^a. This spring pressure serves to hold the stem 23 in position on track 19, and to maintain the position of the binding post as a whole, 10 when the end of the arch wire is removed from the binding post.

The indicating means of the device comprise a casing 29 mounted on a slide 30 which is disposed between parallel tracks 15 31. The slide 30 is secured to a nut 32 which extends through a slot in the cover 2 of the main casing of the device. Engaging with the nut 32 is a threaded shaft 33, which has bearings in lugs 34 and 35 depending from the under side of cover 2, and which is provided with a micrometer wheel 36 similar to that described for producing movement of the slide 4. The slide 30 is formed to provide a pointer 37, which co- 20 operates with a scale 38 for showing movement of the indicating means.

The operating elements of the indicating means proper comprise a yoke or frame 39 within the casing 29. Movement of this 30 yoke is resisted by a pair of coiled springs 40 which are attached to lugs 41 in the interior of the casing. Movement of the frame 39 is transmitted to a pointer 42 by means of an arm 43 engaging a segmental 35 rack 44 which in turn engages a pinion 45 on the pointer supporting shaft 46. A coiled spring 47 tends to restore the pointer to initial position upon retraction of the frame 39 by the coiled springs 40. A calibrated scale 48 is provided as a cover for casing 29, and co-operates with the pointer 40 in giving the desired readings.

The contact means for transmitting movement to the frame 39 comprise a rod 45 49, which is integral with the frame and extends from the point 50 thereon. This rod 49 has a frictionless mounting in a tubular extension 51 of the casing 29. This mounting comprises a light coiled spring 50 52 which is secured at one end to the tubular extension 51 and at its other end to the rod 49. At the outer extremity of rod 49 is a ferrule 53 for contacting the wire to be tested. As shown in Figure 6, this ferrule 55 is notched at its outer end to embrace the wire to be tested; and has at the base of the notch 54 a rounded bearing point 55, so that a point bearing with the wire is provided.

In use of the device in orthodontia a wire 60 A is mounted in curved position with its ends held by the binding posts 22. The length of the wire itself, together with the mutual adjustment of the binding posts gives the desired curvature to fit 65 the mouth of the patient the tooth or teeth

of whom are to be straightened. To this wire arch A a length of straightening wire B is then attached by soldering one end of the straightening wire to the arch wire, leaving the other end of the wire B free. 70 The turn table 15 is then swung to the desired degree to indicate the direction of pressure to be exerted on the tooth or teeth.

The arch wire A exerts a pressure on the 75 lingual or labial surfaces of the teeth to secure a normal occlusion. The short wire B exerts pressure on a single tooth or on relatively few teeth. As its effect is concentrated rather than distributed, this wire is desirably relatively light. It effects a 80 special straightening effect independent of the effect of the arch wire A.

The slides 4 and 30 are then moved so that the ferrule 53 on the end of the rod 49 of the indicating means is in contact with 85 the wire B at a desired starting point for the estimation of pressure. Further, and exactly measured, movement of the slide 4 will indicate, by means of the pointer 42 and calibrated scale 48, the pressure exerted by 90 the wire during such movement at its point of contact with the rod 49. After the desired readings for movement through various distances have been taken at any one point, readings may be taken along the wire 95 B by movement of the indicating means in a direction at right angles to that of the slide 4 which carries the wire holding means.

If so desired the expansive pressure exerted by the arch wire itself may be exactly 100 estimated. This is effected by bending the arch wire A to approximate form, and clamping its ends in the binding posts 22. The distance separating the binding posts, and consequently the ends of the arch wire, 105 may be observed on a scale 19^a marked off on the track 19. One end of the arch wire is then released from its binding post, and is bent outward a distance which may be roughly noted on the scale 19^a, so as to take 110 a permanent set in this position. The turn table 15 is then rotated to present the loose end of the arch wire to the head 53 of rod 49. By then moving the slide 4 toward the indicating means the pressure required to 115 move the loose end of the arch wire back to its binding post may be observed. This is conversely the pressure which this free end is capable of exerting through the distance noted by means of scale 5 and micrometer 120 13. This operation may be performed successively on both ends of the arch wire.

If the wire B is found to exert too light pressure, or a dangerous degree of pressure, an arch A carrying a pressure wire B 125 of greater or lesser length or gauge may be substituted and similarly tested. These tests may be continued until an arrangement providing exactly the right pressure for the purpose has been secured. As the distance 130

which the straightening wire B extends outwardly from the arch wire A affects the pressure exerted by the straightening wire, it is of great advantage that the distance 5 separating every part of the straightening wire from the arch wire may be noted by moving the platform 4 and observing the distance moved on the scale 5.

The pressure exerted in other directions 10 by an arch wire, or by a straightening wire attached thereto, may be estimated by means of the attachment shown in Figures 7 to 9 inclusive of the drawings. This attachment comprises a frame member 56, which 15 has depending therefrom split fastening members 57 over which are collar members 58 carrying split extension pins 58^a. Spaced sockets 59 are provided in the platform 4 for receiving either the fastening members 20 57 themselves, or the split extension pins 58^a. By means of this arrangement the height of frame member 56 with respect to platform 4 may be regulated; by either inserting the fastening members 57 themselves 25 in the sockets, or adjusting the position of extension pins 58^a and inserting the pins in the sockets.

Extending through a slot 60 in the frame member 56 are the shanks of screws 61, engaged by threaded caps 62. The head 63 of each of the screws is kerfed throughout substantially its entire depth, and has exteriorly thereof a beveled face 64 engaging an interiorly beveled ring 65. A washer 35 66 is interposed between the frame member 56 and the ring 65.

In mounting the wire C for testing, the caps 62 are loosened to permit mutual adjustment of the screws 61 in the frame member 40 and the extremities of the wire C are inserted in the deep kerfs in the heads 63 of the screws. The caps 62 are then screwed down, this action not only fixing the binding posts as a whole in their position on frame 45 56, but also drawing up the heads 63 of the screws into their rings 65, and so decreasing the width of their kerfs as to clamp the ends of the wire firmly in position.

50 When mounted in this position the arch wire may be tested for distance of upward and downward movement, and upward and downward pressure exerted on the teeth of a patient. To make this reading the arch 55 wire is bent from points adjacent the ends of the arch wire, and is inserted in the binding posts. By then moving the slide toward the rod 49, the distance through which the loop is moved in making the arch wire perpendicular, and the pressure required to do so, may be noted. One reading necessarily indicates the pressure and distance in either upward or downward movement, because the difference in obtaining these movements 60 65 is merely a matter of reversing the arch

wire as applied in the mouth of a patient.

It should be understood that the device is usually employed repeatedly in successive tests during the process of moving the teeth of a patient to secure normal occlusion. It 70 should be understood in this connection that a straightening wire is tested for a short movement, without excessive pressure, and allowed to remain in the mouth of the patient for a number of days. The wire is 75 then removed and the estimation for a further movement is made from the point to which the straightening wire was previously bent. In a successful treatment the total distance through which the tooth or 80 teeth have been moved is increased moderately by each application of the straightening wire until normal occlusion has been obtained.

With the mounting for an arch wire C, as 85 shown in Figure 3; in second, and subsequent applications of the wire, the point at which the slide 4 rests with the arch in contact with head 53 is first noted on the scale 5. The arch wire is then removed from the 90 binding posts, and is bent further in the same direction an approximated distance. The arch wire is then returned to the binding posts, and the slide moved until the arch 95 wire is again in contact with head 53. The difference between the scale readings before and after the additional bending gives the distance of such additional bending. The slide is then again moved forward a distance equal to such difference, and the pressure 100 noted.

With the mounting for an arch wire A, as shown in Figures 1 and 2, readings for applications subsequent to the first may be made in the following manner. The arch 105 wire, in the shape in which it was last applied, is placed in the binding posts 22, and the readings on the scale 19^a noted. The arch wire is then removed, and bent so that one of the ends extends a greater distance, 110 as may be observed roughly from scale 19^a. The other end is then placed in its binding post, and brought into contact with head 53. The pressure exerted in bringing the free end back to position for engagement 115 with the binding post may then be observed, and the exact distance of movement also observed by reference to scale 5 and micrometer scale 13.

In making additional readings for increased tooth movement to be caused by auxiliary straightening wire B, the procedure is in general that used in making successive readings for arch wire C. The wire B, as last used is brought in to contact with head 53, and a reading taken on scale 5 and micrometer scale 13. The arch wire is then removed; and either a new wire soldered on, or the old wire bent further. This new arrangement is then estimated by bringing 120 125 130

auxiliary straightening wire B into contact with head 53, and the slide moved forwardly into its exact previous position, as shown by scale 5 and micrometer scale 18.

5. In making all determinations, the slide 30, which carries scale casing 29, may be moved in the previously described manner to secure readings at observed points along the wire.

10. As shown in Figure 11 of the drawings, the instrument may also be used to determine the pressure exerted by a screw socket applied to one end of the arch wire. In such use of the device, a screw socket 67, 15 having a threaded engagement with one end of the arch wire, is clamped in one of the binding posts 22 without the exertion of sufficient pressure thereon to prevent turning of the socket. The other end of the 20 wire is clamped in the other binding post 22. The curve of the arch wire is then brought into contact with the head 53 of rod 49, and the socket is turned through all or part of a revolution. The pressure 25 exerted by turning the screw socket may be noted on the scale 48.

It should be understood that the principle of the present invention, with a device of various sizes but substantially unaltered 30 form, may be applied for testing wire to be used in various connections other than orthodontia.

What I claim is:

35. 1. A device for estimating the pressure exerted by a wire comprising wire clamping means, pressure indicating means having a member arranged to contact with the wire, said wire clamping means and pressure indicating means being separately mounted for rectilinear movement toward each other during testing of the wire, and manually operable means for producing relative movement between said wire clamping means and said pressure indicating means.

45. 2. A device for estimating the pressure exerted by a wire comprising a carrier mounted for sliding movement, wire holding means on said carrier, pressure indicating means in the path of movement of the carrier and having a member arranged to contact with the wire, and means for measuring movement of the carrier toward and from the indicating means.

55. 3. A device for estimating the pressure exerted by a wire comprising a carrier mounted for measured sliding movement, wire holding means on said carrier, and pressure indicating means in the path of movement of the carrier and having a member 60 arranged to contact with the wire and mounted for measured movement in a path at approximately right angles to that of the carrier.

65. 4. A device for estimating the pressure exerted by a wire comprising a carrier

mounted for sliding movement, wire clamping means on said carrier, pressure indicating means having a member arranged to contact with the wire, a scale adjacent the carrier for estimating movement thereof, and 70 manually operable micrometer means for producing movement of the carrier and for measuring distance moved thereby between subdivisions of the scale.

5. A device for estimating the pressure 75 exerted by a wire comprising a carrier mounted for sliding movement, wire holding means on said carrier, pressure indicating means having a member arranged to contact with the wire, manually operable means 80 for producing movement of the carrier toward and from said pressure indicating means, and a slidable mounting for said pressure indicating means arranged for movement at approximately right angles to 85 the path of movement of the carrier.

6. A device for estimating the pressure exerted by a wire comprising a carrier mounted for sliding movement, wire holding means on said carrier, manually operable 90 micrometer means for producing movement of the carrier and for measuring distance moved thereby, slidably mounted pressure indicating means arranged for movement at approximately right angles to 95 the path of movement of the carrier, and manually operable micrometer means for producing movement of the indicating means and for exactly measuring distance moved thereby.

100 7. A device for estimating the pressure exerted by a wire comprising a slidably mounted carrier, wire holding means rotatably mounted on said carrier, pressure indicating means having a member arranged to contact with the wire, and manually operable means for producing movement of the carrier toward and from the pressure indicating means.

105 8. A device for estimating the pressure exerted by a wire comprising a slidably mounted carrier, wire holding means rotatably mounted on said carrier, pressure indicating means having a member arranged to contact with the wire, manually operable means for producing movement of the carrier toward and from the pressure indicating means, and a scale adjacent the carrier for estimating the distance moved thereby.

110 9. A device for estimating the pressure 120 exerted by a wire comprising a carrier mounted for sliding movement, wire holding means rotatably mounted on the carrier, pressure indicating means having a member arranged to contact with the wire, a scale 125 adjacent the carrier for estimating distance moved thereby, and manually operable micrometer means for producing movement of carrier and for measuring distance moved thereby between subdivisions of the scale.

10. A device for estimating the pressure exerted by a wire comprising a carrier mounted for sliding movement, wire holding means rotatably mounted on said carrier, pressure indicating means having a member arranged to contact with the wire and slidably mounted for movement at approximately right angles to the path of movement of the carrier, and manually operable micrometer means for producing movement of the indicating means and for exactly measuring distance moved thereby.

11. A device for estimating the pressure exerted by a wire comprising wire clamping means, pressure indicating means having a member arranged to contact with the wire, said wire clamping means and pressure indicating means being separately mounted for rectilinear movement toward each other during testing of the wire, manually operable means for producing relative movement of said wire clamping means and said pressure indicating means, and a scale for indicating the distance of such relative movement.

12. In a device for estimating the pressure exerted by a wire the combination of a slidably mounted carrier, a rotatable member for holding the wire on said carrier, a scale on the carrier for indicating the angular position of the rotatable member for holding the wire thereon, and a binding post on said rotatable member for receiving an end of the wire.

13. In a device for estimating the pressure exerted by an arched wire the combination of a slidably mounted carrier, a rotatable member on said carrier, a scale on the carrier for indicating the angular position of the rotatable member thereon and binding posts mutually adjustable on said rotatable member and arranged to each receive one end of the arched wire.

14. In a device for estimating the pressure exerted by an arched wire the combination of a slidably mounted carrier, a rotatable member on said carrier, a scale on the carrier for showing the angular position of the rotatable member for holding the wire with respect to the direction of movement of the carrier, a pair of binding posts mutually adjustable in said track and arranged to each receive one end of the arched wire, and manually operable micrometer means for producing movement of the carrier and showing the distance moved thereby.

15. In a device for estimating the pressure exerted by a wire the combination of a slidably mounted carrier, a rotatable member on said carrier, binding posts mutually adjustable on said rotatable member for holding the wire, and pressure indicating means having a member arranged to contact with the wire held by said binding posts.

16. In a device for estimating the pressure exerted by a wire the combination of a slid-

ably mounted carrier, a rotatable member on said carrier, binding posts mutually adjustable on said rotatable member for holding the wire, and pressure indicating means mounted for movement in a path at approximately right angles to the path of movement of the carrier and having a member arranged to contact with the wire.

17. In a device for estimating the pressure exerted by a wire the combination of a slidably mounted carrier, a rotatable member on said carrier, binding posts mutually adjustable on said rotatable member for holding the wire, manually operable micrometer means for producing movement of the carrier and showing the distance moved thereby, pressure indicating means mounted for movement in a path at right angles to the path of movement of the carrier and having a member arranged to contact with the wire held by the binding posts, and manually operable micrometer means for producing movement of the indicating means and for measuring the distance moved thereby.

18. In a device for estimating the pressure exerted by a wire the combination of a slidably mounted carrier, a rotatable member on said carrier and having a track therein, and a pair of binding posts mutually adjustable in said track and arranged each to receive an end of the wire to be tested, each of said binding posts comprising a tubular stem, a rod passing through the stem having a threaded portion extending thereabove and a portion engaging said track, a cap engaging the threaded portion of said rod, and yielding means interposed between said stem and said cap.

19. In a device for estimating the pressure exerted by a wire the combination of a slidably mounted carrier, a rotatable member on said carrier, a scale on the carrier for indicating the angular position of the rotatable member thereon, binding posts mutually adjustable on said rotatable member and arranged to receive an end of the wire to be tested, and a scale for indicating movement of the binding posts on said rotatable member.

20. As an article of manufacture a binding post construction comprising a track having an upper portion supported to provide a path therebeneath, a tubular stem on said track, a rod passing through said stem having a threaded portion extending thereabove and a portion engaging the under surface of the upper portion of said track, a cap engaging the threaded portion of said rod, and yielding means interposed between the cap and stem causing the tubular stem and the track engaging portion of the rod to remain in tight contact with the track when the binding post is retaining no wire therein.

21. As an article of manufacture a binding post construction comprising a track having an upper portion supported to provide a path therebeneath, a tubular stem having a chamber therein on said track, a rod passing through said stem having a threaded portion extending thereabove and a portion engaging the under surface of the upper portion of said track, a cap engaging 10 the threaded portion of said rod, and a

coiled spring seated in the chamber in the stem and bearing against the cap for maintaining a frictional engagement between the track engaging portion of the rod and the track when no material is being held in the 15 binding post.

In witness whereof, I hereunto set my hand.

RUSSELL E. IRISH.
